UNITED STATES PATENT OFFICE.

SAMUEL WILLIAM TURNER, OF LONDON, ENGLAND, ASSIGNOR TO YOST WRITING MACHINE COMPANY, OF ILLION, NEW YORK, A CORPORATION OF NEW YORK.

TYPE-WRITING MACHINE.

1,124,557.

Specification of Letters Patent.

Patented Jan. 12, 1915.

Application filed February 25, 1913. Serial No. 750,515.

To all whom it may concern:

Be it known that I, SAMUEL WILLIAM TURNER, a subject of the King of Great Britain and Ireland, resident of London, 5 North, England, have invented certain new and useful Improvements in Type-Writing Machines, of which the following is a specification.

My invention relates to typewriting machines and more particularly to tabulating mechanism.

The objects of my invention, generally stated, may be said to be as follows:—1st, to provide improved tabulator means by which 15 any one of a comparatively large number of columns may be selected; 2nd, to provide such a column selecting mechanism without the necessity of providing a correspondingly large number of column selecting keys; 3rd, 20 to provide improved means by which backward, as well as forward, tabulation may be effected; 4th, to provide improved means by which the same stops are operative to arrest the carriage at the same letter space position 25 during backward tabulation that they are to arrest the carriage during forward tabulation; 5th, to provide means by which one tabulator stop may be interposed in the path of another and a release of the carriage simultaneously effected, or by which such interpositioning of one stop in the path of another may be effected without releasing the carriage; 6th, to provide automatically operating means by which the tabulating mechanism 30 is operative at one time for column selection only and at another time for denominational selection only; 7th, to provide means by which the carriage in its line of travel automatically determines whether the tabulating mechanism is operative for column selection or for denominational selection; 8th, to provide means by which the tabulating mechanism may be rendered operative indefinitely as a column selector or 35 as a denominational selector; 9th, to provide automatically operating means by which a single key is operative at one time to select a columnar position of arrest and at another time to select a denominational 40 position of arrest; and 10th, to provide means of the character specified above which may be readily embodied in existing styles of typewriting machines without modifying, or materially modifying, the structural features 45 of said machines as they now exist.

To the above and other ends, which will hereinafter appear, my invention consists in the features of construction, arrangements of parts and combinations of devices set forth in the following description and particularly pointed out in the appended claims. 50

In the accompanying drawings wherein like reference characters indicate corresponding parts in the various views, Figure 1 is a fragmentary side view, with parts removed, of one form of typewriting machine embodying my invention. Fig. 2 is a fragmentary detail plan view showing the tabulator controlling keys and index and some of the associated parts. Fig. 3 is a fragmentary detail vertical transverse sectional view on an enlarged scale, the section being taken through the column stop bar and showing the column stops and some of the associated parts. Fig. 4 is a fragmentary rear elevation of the machine with some of the parts removed. Fig. 5 is a detail fragmentary perspective view of the stop setting key and some of the parts associated therewith. Fig. 6 is a detail transverse sectional view of the 55 same. Fig. 7 is a detail front view of the guide plate for the release key lever, the lever being shown in section. Fig. 8 is an enlarged detail fragmentary rear elevation of the column stop bar and some of the associated parts, the view showing a single column stop in place. Fig. 9 is a detail fragmentary front view, partly in section, showing a part of the carriage, a column stop, the stepped stops and some of the coöperating 60 parts. Fig. 10 is a like view of the same showing a different disposition of the parts. 65

I have shown my invention embodied in the present instance in a No. 20 Yost machine in which the invention may be readily included without modifying, or materially modifying, the structural features of said machines as they now exist. It should be understood, however, that the invention may be embodied in various styles of typewriting machines and may be variously modified to effect such an embodiment. 70

The frame of the machine comprises side plates 1, a rear cross plate 2, and top plates 3 and 4. Fixed grooved guide rails 5 are 75 supported on the side plates of the machine and receive anti-friction balls or rollers 6 which are likewise received in oppositely grooved tracks or guide ways 7 on a carriage truck 8. A platen frame 9 is mounted 80

110

in the usual manner on the truck and supports a cylindrical platen 10. The carriage is thus supported for movement from side to side of the machine, being propelled from right to left, or in the direction of its feed, by a spring drum 11 connected to the carriage by a band or cord 12. The type bars (not shown) are actuated by finger keys 13 and strike upwardly and rearwardly against the front face of the platen.

Depending lugs 14 are formed on the carriage truck 8. Arms 15 are pivoted to these lugs at 15^a, the arms being connected to a feed rack 16 which meshes with a feed pinion 17. The shaft of this feed pinion extends through a drum 18 which contains a retarding device for controlling the movement of the carriage when the latter is freed from the control of the escapement mechanism. The rotative retarding element contained within the drum 18 is connected with a sleeve 19 which surrounds the shaft of the feed pinion, the lower end of said shaft being supported by a bearing screw 20 carried by a fixed part of the machine. A collar 21 surrounds the sleeve 19 and is provided with clutch teeth 22 at the lower edge thereof. This collar is slotted at 23 for the reception of a screw or pin 24, threaded into an opening tapped in the sleeve 19. Coöoperating clutch teeth 25 extend upwardly from a second sleeve 26 which loosely surrounds the shaft of the feed pinion. A yoke 27 is pivoted at 28 to the sleeve 26 and is provided with a pawl 29. A spring 30 is connected at one end to the yoke-like member 27 and is fixed at its opposite end, as at 31, to the sleeve 26. The pawl 29 is adapted to engage ratchet teeth 32 formed on a hub 33 of an escapement wheel 34, and it is by this pawl and ratchet that the shaft and escapement wheel are coupled to turn together in one direction, as will hereinafter appear. A spline block 35 is fixed to the shaft of the feed pinion, which shaft also constitutes the shaft of the escapement wheel. This spline 35 is received in a corresponding spline groove formed in the sleeve 26. The construction 50 is such, therefore, that the sleeve 26 is fixed to rotate with the shaft, although said sleeve may receive a vertical movement on the shaft and independently thereof to lift the pawl 29 out of engagement with the ratchet teeth 32, thus effecting a disconnection between the escapement wheel shaft and the escapement wheel in order to free the carriage and enable it to travel free from control of the escapement wheel. An elevation 60 of the sleeve 26 is likewise effective to bring the clutch teeth 25 into coöperative relation with the clutch teeth 22, thus effecting an operative connection between the escapement wheel shaft and the sleeve 19 which is 65 operatively connected to the rotative re-

tarding device contained within the drum 18. It follows, therefore, that when the carriage is disconnected from control of the escapement mechanism the retarding device is at the same time thrown into operation to control the speed of the carriage in its movement from right to left. In order to effect an upward movement of the sleeve 26 and to bring about a release of the carriage, I have provided an arm 36 pivoted at its rear end, as at 37, to a post 38 secured to a fixed part of the machine. The forward end of this arm is bifurcated to form a yoke-like portion 36^a, the two arms of which extend on opposite sides of the sleeve 26. Each arm of the yoke 36^a carries an inwardly projecting pin 39, which extends into a circumferential groove 40 provided on the sleeve 26. An upward movement of the arm 36 is therefore effective to elevate the sleeve 26 and thus effect a release of the carriage in a manner hereinbefore described.

The parts thus far described constitute a portion of the No. 20 Yost machine and further description thereof is deemed unnecessary.

The ordinary tabulator mechanism of the No. 20 Yost machine may be omitted and the devices of my present invention substituted therefor. These devices may be regarded in the nature of attachments which may be readily included in the machine without modifying the structural features thereof as they now exist.

Upwardly and rearwardly extending bracket arms 41 are secured to the carriage truck 8. The right-hand bracket 41 is secured to an upwardly extending lug 42 on the truck by screws 43, whereas the left-hand bracket 41 is secured to the upper face of the truck by screws 44. An upwardly extending foot 45 is formed on each bracket and these feet form supports by which the column stop bar is operatively connected to the brackets in a manner which will herein-after more clearly appear.

The column stop bar in the present construction is in the nature of a double rack bar comprising two parallel rack bars 47, the teeth 48 on one of the rack bars extending toward the teeth on the other bar, as shown in Fig. 8. These rack bars are united by connecting plates 49 and screws 50 to form a frame which supports the various stops which are carried by the carriage. Plate-like column stops 51 are provided at their ends with teeth 52 by which the stops are adapted to engage the oppositely disposed teeth on the rack bars 47. Each plate-like column stop extends longitudinally between the rack bars 47 and is provided with a rearwardly extending contact portion 53, as shown in Fig. 3. These contact or engaging portions 53 of the column stops are disposed in step-like arrangement from one

70

end of the series of stops to the other, the contact portion on the stop at the right-hand of the series being at the highest elevation and the contact portion of the stop at the left-hand of the series being the lowest contact of the series. It will be understood from an inspection of the drawings that each contact has a separate and distinct path of movement with the carriage or a distinctive line of travel, no two contact portions traveling in the same path. These column stops may be adjusted to different positions longitudinally of the rack bars 47, although they are disposed in the order shown so as to maintain the step-shaped arrangement of the contact portions under all adjustments. In the present instance I have assumed the use of sixteen of these column stops 51, which provide for the selection of sixteen columns in a single travel of the carriage from side to side of the machine.

In order to secure the column stops in place in their adjusted positions, I have provided angle plates 54 on the top and bottom rack bars 47. These angle plates are secured to their respective rack bars 47 by headed screws 55 which are received in tapped openings in the bars 47. The upper angle plate 54 has a depending portion 56 which extends to the crowns of the teeth 48 on the associated rack bar and prevents a forward movement of the column stops at the upper ends thereof out of engagement with the upper rack bar 47. A corresponding flange or projection 57 extends upwardly from the lower angle plate 54 and corresponds in a like manner with the lower engaging ends of the column stops to prevent a forward displacement thereof from the lower rack bar. Two parallel locking bars 58 and 59 are arranged on the opposite or rear sides of the rack bars 47 and are movable toward and away from each other into and out of the locking positions. Each of these locking bars is provided with inclined slots 60 through which the stems of headed screws 61 pass, the engaging ends of the screws being received in tapped openings in the associated rack bar 47. Each locking bar is therefore connected through a pin and slot connection 61-60 for movement into and out of operative position. The locking bars when in the operative position shown in Fig. 4 overlap the engaging ends of the column stops in the same general manner as the members 56 and 57 to prevent a withdrawal of the column stops from engagement with the teeth 48 on the rack bars. When, however, the locking bars are in the positions indicated in Fig. 8, any of the column stops may be withdrawn rearwardly from engagement with the teeth 48 to afford an adjustment of the stops. A contractile spring 62 (see Fig. 4) is connected at its

ends to the locking bars 58 and 59, tending to draw them toward each other to the locking position indicated in Fig. 1. The opposite ends of the locking bars are pivotally connected, at 63, to toggle links 64 pivotally connected at their inner ends to a finger piece or button 65 by which the toggle links may be controlled. A movement of the finger piece from the position shown in Fig. 1 to that indicated in Fig. 8 is effective to straighten the toggle and therefore effect a movement of the locking bars 58 and 59 away from each other to the releasing position shown in Fig. 8. It should be understood that when the toggle is in the dead center position, or slightly over the dead center position, as represented in Fig. 8, the toggle links will maintain the locking bars separated and hold them in this position against the power of the spring 62. A slight movement of the finger piece 65 to the left, as the parts appear in Fig. 8, is effective, however, to release the locking bars and enable the spring 62 to move them back into the locking position represented in Fig. 4. The frame in which the column stops are mounted is connected to the carriage in such a manner as to afford a lost motion connection between the carriage and the frame or double rack bar carrying the entire series of column stops. Thus, from an inspection of Figs. 4, 9 and 10 it will be seen that each foot piece 45 of the associated bracket 41 is connected by means of screws 66 to a plate 67. Each plate 67 is slotted at 68 in the general direction of the travel of the carriage. A pin, which is in the nature of a headed screw 69 is received in each slot and extends freely therethrough into a tapped opening in the associated rack bar 47. A pin and slot connection 69-68 is thus provided at the top and bottom of each plate 67 where connection is made between the plate and the rack bars 47. Each bracket 41 is connected in a like manner to the double stop carrying bar or frame. The screws 66 which connect one of the plates 67 to the associated foot piece 45 are also employed to secure a bracket plate 70 to the bracket and carriage. An upwardly extending arm 71 from this bracket plate provides means by which one end of a contractile spring 72 is connected to the bracket plate, the opposite end of said spring being connected to a pin 73 which projects from the upper rack bar 47. A corresponding downwardly extending bracket arm 71^a provides means by which one end of a contractile spring 74 is connected, the opposite end of this spring being secured to a pin 75 projecting from the lower rack bar 47. The contractile springs 72 and 74 exert a force to normally maintain the stop carrying bar disposed with relation to the carriage in the position shown in Fig. 10 with each screw 69 in the left-hand end of

its slot 68. When, however, a stop engages one of the column stops to arrest the carriage, and the latter is moving in the direction of its feed, the stop carrying bar or frame will be arrested but the carriage, under the power of its spring drum, will continue to move a limited distance until the plates 67, moving with the carriage, bring the right-hand ends of the slots 68 into engagement with the screws 69, thereby arresting further movement of the carriage to the left. At this time the power of the carriage spring overcomes the power of the springs 72 and 74. As soon, however, as the obstructing stop is moved out of the path of the engaged column stop the springs 72 and 74 will effect a longitudinal movement of the stop carrying bar to the left independently of the carriage until the screws 69 reach the left-hand ends of the slots 68, as shown in Fig. 10, when the stop carrying bar and carriage will again move together as one part. The purpose of this bodily shifting or displacement of the entire series of column stops with reference to the carriage for a limited distance is to provide for the arrest of the carriage by the same stops at the same letter-space position during both forward and backward tabulation, as will be herein-
after more fully explained.

I have provided on the frame of the machine a single selecting stop which is co-operative with the different column stops to select a columnar position of arrest of the carriage. The actuating means for this selecting stop is contained within a housing arranged on the right-hand side of the machine. In Fig. 1 the parts are shown with the right-hand cover plate of the housing removed. This housing comprises a plate 76 which is secured to the right-hand side plate 1 of the machine by shouldered screws 77. This plate supports a shouldered pivot screw 78 on which a bell crank lever 79 is pivoted. The rearwardly extending arm of this bell crank lever is pivoted at 80 to an upwardly extending bar 81 which carries a forwardly projecting selecting stop 82. The forwardly projecting arm of the bell crank lever 79 is pivotally connected to the rear end of a rod 83. The other end of this rod is pivoted by means of a screw 84 to a slide 85 formed as a part of a selecting key 86. This slide 85 is received in a slot 87 which extends longitudinally fore and aft of the machine in a plate 88 connected by screws 89 to the housing. This slide is thus mounted and guided for movement fore and aft of the machine in the slot 87. The selecting key 86, which is formed as a part of the slide or block 85, extends above and below the slot on the outside of the plate 88. A double spring 90 is secured at the center portion thereof to the inner side of the slide or block 85, the free ends 91 of the spring bear-

ing against the inner face of the plate 88 on opposite sides of the slot 87 therein. The pressure of this spring therefore is exerted to force the finger piece or key toward the plate 88 and to prevent the slide from being displaced outwardly from the slot. The headed screw 84, which connects the link 83 to the slide 85, may also be employed to connect the spring 90 to the slide. The plate 88 is provided above the slot 87 therein with a series of depressions 92. A detent, which in the present instance is in the nature of a ball 93, is received in an opening 94 in the finger piece 86. This detent ball is pressed into one or another of the depressions 92 by a spring 95, as the ball is brought into register with one or another of the depressions. The purpose of this construction is to provide detent means for holding the selecting key 86 against accidental displacement in any one of sixteen different positions to which it may be moved and for assuring a proper positioning of the key and slide in each of said positions. The slide may be limited in its movements in opposite directions in the slot 87 by contact screws 96 and 97 threaded into tapped openings in the slide 85 and the heads thereof contacting with the end walls of the slot.

From the foregoing description it will be understood that a movement of the selecting key 86 to any one of sixteen different positions is effective to produce a corresponding movement of the bell crank lever 79 around its pivot 78. This movement of the bell crank is effective to raise or lower the stop carrying bar 81 to any one or sixteen different positions and to bring the stop 82 thereon into register with a contact portion on any one of the sixteen column stops 51. The stop carrying bar 81 under control of the key 86 receives substantially a rectilinear movement in the direction of its length, and during this movement of the bar the stop 82 is not actually brought into co-operative relation with any of the contact portions of the column stops, but is merely set in register with one of them. The movement of the selecting stop 82 into the path of the contact portion of one of the column stops is effected by a rotative movement of the stop carrying bar 81 around its pivot 80 by means to be herein-after described. The upper portion of the stop carrying bar is guided between parallel plates 98 which are maintained spaced apart by a spacing block 99 (see Figs. 1 and 4) and are connected together by screws 100. One of the plates 98 is formed as a rearwardly projecting flange of a bracket plate 101 which is secured in the frame of the machine by screws 102 (see Fig. 4). The upper end portion of the stop carrying bar 81 is thus guided for vertical movement and for a limited movement fore and

aft of the machine between the block 99 and a stop 98^a (see Fig. 1). A second bell crank lever 103 is pivoted on a shouldered pivot screw 104 secured to the bracket plate 76. The upwardly extending arm of this bell crank lever is doubled at its upper end, as at 103^a, to form two rearwardly extending parallel plates 105 between which the stop carrying bar 81 is received. A screw 106 extends between these plate-like members 105 in the rear of the stop carrying bar and a second screw 107 extends between the plates 105 in front of the stop carrying bar. A spring, which is designated as a whole by the reference numeral 108, is coiled about the screw 106 and bears at its upper free end 109 against the rear edge of the stop carrying bar 81. The lower end 110 of this spring also bears against the rear edge of the stop carrying bar 81. The power of this spring, therefore, is exerted to press the stop carrying bar toward the front of the machine and into contact with the screw 107 which limits the forward movement of the stop under the power of its spring.

The forwardly projecting arm of the bell crank lever 103 is connected by a depending link 111 to a key lever 112 which is pivoted on the pivot screw 78. This key lever extends through a slot 113 (see Fig. 7) in a guide plate 114 which forms part of the housing which contains the actuating devices for the selecting stop. The forward end of the key lever 112 is provided with a finger key 115 by which it may be depressed against the power of a spring 116 connected at one end to the key lever 112 and at its opposite end to a screw 117 projecting from the bracket plate 76. The slot 113 in the guide plate (see Fig. 7) has a contact 118 formed by the lower wall thereof, and a second contact 119 is formed by a shoulder at the termination of an inclined wall 120 of the slot.

A direct downward pressure on the release key 115 is effective to depress the key lever 112 until it is arrested by engaging the bottom wall 118 of the slot. When, however, a slight lateral pressure to the right is given the key during a depression thereof, this will guide the key lever along the right-hand wall 120 of the slot until the key lever is arrested by engaging the shoulder 119 before a complete dip is given to the key. The purpose of this construction will hereinafter more clearly appear. A second link 121 is connected to the key lever 112 and extends upwardly therefrom to a lever 122 pivoted at 123 on a shouldered pivot screw which is supported by a bracket 124 fixed to the frame of the machine. The inner end of the lever 122 extends beneath the carriage releasing arm 36 so that an upward movement of the inner end of the lever

122 is effective to move the arm 36 upwardly, thereby effecting a release of the carriage from the control of its escapement mechanism in a manner hereinbefore explained.

From an inspection of Figs. 1 and 2, it will be observed that the selecting key 36 is provided with a pointer 125 which extends to the left from the key and overlies an index plate 126 detachably secured by any suitable means to a substantially horizontally disposed flange 128 formed integral with the plate 83. Thus the index plate 126 may be received longitudinally under overlapping flanges 127 of a metallic plate 80 which is secured to the flange 128 by screws 129. This index plate in the present instance is in the nature of a plate on which inscriptions may be made and erased therefrom if desired when a change of the inscription is to be effected. The index plate is preferably divided as by lines 130 to provide spaces 131 in which suitable indices may be inscribed, such, for example, as the titles employed at the heads of different columns to be selected with the aid of the tabulator mechanism. I also preferably provide numerical indices 132 by which the different columns across the sheet may be indicated.

In the use of the mechanism, if the operator should move the selecting key until the pointer 125 thereon is in register with, say, the index numeral "4", this will indicate that the tabulator is set to select the fourth column in the line of travel of the carriage from right to left. The effect of this movement of the selecting key is to turn the bell crank lever 79 the requisite distance to elevate the stop carrying bar 81 in order to bring the stop 82 thereon into register with the fourth column stop of the series, counting from left to right. When the selecting key 36 is adjusted in the manner described, it will be retained indefinitely in its adjusted or set position by the detent 93, and the parts controlled by the key will likewise be maintained indefinitely in the positions to which they have been set. A direct downward pressure exerted on the release key 115, after the selecting key 36 has been adjusted, is effective to turn the bell crank 103, thereby moving the stop carrying bar 81 around its pivot until arrested by the stop 98^a. The effect of this is to move the stop 82 into the path of the contact portion on the column stop with which the stop 82 is in register. The depression of the release key 115 is likewise effective to turn the lever 122, thereby elevating the release arm 36 to release the carriage from control of the escapement mechanism. The carriage being thus freed will travel from right to left until arrested by the co-operation of the selected column stop and the key controlled stop 82. It will

thus be understood that any one of sixteen different columns may be readily selected with the aid of the single selecting key 86, and when the releasing key 115 is depressed the carriage will move from right to left until the selected columnar field has arrived at the printing point.

During the arrest of the carriage by the coöperation of one of the stops 51 with the 10 selecting stop 82 in the movement of the carriage from right to left, or in the direction of its feed, the carriage will, as hereinbefore explained, move a slight distance independently of the series of column stops 51 after the stop 82 and one of the stops 51 are brought into coöperation. This is due to the pin and slot or lost motion connections 15 68-69 between the carriage and the stop carrying bar or frame, as hereinbefore explained. It will be understood that the final point of arrest of the carriage takes place after the lost motion has been taken up, and the extent of this lost motion is indicated in Figs. 9 and 10 by the dotted lines *a* and *b*. 20 The distance between these lines indicate the extent of lost motion or movement of the carriage effected after the stops are brought into coöperation. The purpose of this feature of the construction is, as has been previously pointed out, to enable the carriage 25 to be arrested at the same letter space position by the coöperation of the same stops during both a backward and a forward tabulation. If, for example, a backward tabulation 30 is to be effected, the selecting key 86 is moved fore and aft of the machine, to set the stop 82 to arrest the carriage at a given columnar field, determined by such setting of the stop. The operator then depresses the 35 key 115, at the same time giving a slight lateral pressure of the key to the right and thereby arresting the key through the coöperation of the lever 112 with the shoulder 119 on the guide plate 114. The limitation 40 of the depression of the key 115 thus effected results in moving the stop 82 forwardly into coöoperative relation with the registering projection on one of the column stops to the left of the stop 82. While the limited depression 45 of the key 115 is effective to move the stop 82 forwardly into operative position, it is ineffective to release the carriage from the control of the escapement mechanism. This is due to the fact that there is sufficient lost motion between the levers 36 and 122 (see Fig. 4) to enable the limited depression of the key 115 to be effected without throwing the sleeve or clutch member 26. It follows, therefore, that although the stop 50 82 has been moved to operative position the carriage will remain under control of the escapement mechanism to hold it against movement in the direction of its feed. The operator may, nevertheless, move the carriage by hand at this time from left to right

until it is arrested by the coöperation of the stop 82 with the selected column stop.

Fig. 10 shows the positions of the parts at the instant a column stop 51 co-acts with the projected selecting stop 82 during the backward movement of the carriage. It will be seen that at this time the screws 69 are in the left-hand ends of the slots 68 so that there is no relative movement between the carriage and the stop carrying bar or frame when the carriage is arrested during its movement from left to right. The point of arrest, therefore, will be at a position indicated by the dotted line *a* in Fig. 10. The escapement mechanism being operative or effective at this time, the carriage will be prevented from moving in the direction of its feed, thus holding the carriage in the position at which it has been arrested by the coöperation of the stops. A release of the key 115 at this time withdraws the stop 82 from the path of the co-acting projection 55 53 on the column stop and an arrest of the carriage is thus effected at the selected columnar field. If, on the other hand, the arrest of the carriage is effected by these same stops 82 and 51 during the movement of the carriage from right to left, a movement of the carriage independently of the stop bar will be effected after said stops are brought in contact. The distance of such independent movement corresponds to the distance between the dotted lines *a*, *b* in Figs. 9 and 10, and this distance corresponds to the thickness of the contact portions of the two co-acting stops 82 and 51. It will be understood, therefore, that the arrest of the carriage by these stops during the movement of the carriage from right to left compensates for the thickness of the co-acting 60 stops so that the final arrest of the carriage by the stops will be at a point indicated by the dotted line *a* instead of at the line *b* where they are first brought into engagement. This line *a* indicates the same point of arrest by these co-acting stops during the movement of the carriage from left to right so that in both instances the carriage will be arrested at the same letter space position. Otherwise stated, the carriage is 65 arrested by the stops 82 and 51 during the movement of the carriage from left to right without any lost motion being effected between the carriage and the stop carrying bar, the point of arrest being indicated by the dotted line *a* through the coöperation of the right-hand face of the contact portion of the column stop 51 with the left-hand face of the projected selecting stop 82. On the other hand, during the movement of 70 the carriage from right to left, the left-hand face of the engaging portion of the column stop 51 will co-act with the right-hand face of the projected selecting stop 82. But after this engagement is effected 75

the carriage will continue its movement to the left by reason of the lost motion connection 68-69 a distance corresponding to the thickness of the engaging portions of the two coöperating stops 82 and 51, so that the final point of arrest of the carriage will be at a position indicated by the dotted line a. The carriage will thus be arrested by coöperation of the same stops at the same letter space position, whether the tabulation is effected by a forward movement of the carriage in the direction of its feed or by a backward tabulation in the direction opposite to that of its feed. As hereinbefore explained, as soon as the selecting stop 82 is withdrawn from engagement with the coöperating stop 51, after a forward tabulation has been effected, the springs 72 and 74 shift the stop carrying bar or frame longitudinally to reëstablish the normal relations between the carriage and the stop carrying bar.

It is sometimes desirable to provide columnar selection during one portion of the travel of the carriage and a denominational selection at another portion of the travel of the carriage. In order to bring about this result I contemplate providing one or more stepped stops, each of which is designated as a whole by the reference numeral 133. Each of these stops comprises two parallel engaging members 134 which correspond in construction to the column stops 51 except that they have no engaging projections corresponding to the projections 53 on the column stops. Each pair of engaging members 134 is united by a pair of shouldered rivets 135. The frame thus formed by the parallel members 134 and shouldered rivets 135 has a stepped stop member 136 fixedly secured thereto at its rear side. This stepped stop member is provided with stepped stops 137 and is secured in place by screws 136 (see Fig. 4). Each of these stepped stops 137 has a path of travel which corresponds to one of the projections 53 on the column stops, there being sixteen stepped stops shown in the present instance to correspond to the sixteen stop projections 53 on the column stops. Moreover, the stepped stops 137 are in the same transverse vertical plane as the engaging portions 53 on the column stops so that the selecting stop 82 may be moved into the paths of the stops 137 as well as into the paths of the projections 53.

The construction and arrangement of the parts is such that each stop member 133 may be adjusted to different column determining positions along the rack bar frame in the same manner as the column stops 51. In the present instance I have shown but one stepped stop member 133, that being located to the right of the series of column stops 51. It should be understood, however, that any desired number of these

stepped stop members 133 may be employed and that they may be adjusted to different positions along the stop bar. Moreover, all of the column stops 51 may be removed and the stepped stops 133 employed in lieu thereof; or the stepped stops may be removed and the column stops 51 alone employed; or, as shown in the present instance, the column stops 51 up to, say, sixteen in number, may be employed for coöperation with the selecting stop 82 during the first portion of the travel of the carriage in its movement from right to left and a stepped stop 138 may be employed at the right of the series of column stops so that after the column stops have passed the selecting stop 82, this latter stop may be employed in connection with the stepped stop to select any denominational position of arrest in the last columnar field, which field is determined by the position to which the stepped stop 133 has been adjusted. If desired, the stepped stop 133 may be arranged to the left of the series of column stops 51, in which event a denominational selection may be effected in the first columnar field in the movement of the carriage from right to left, and the different columnar positions of arrest could be afterward selected. In the particular arrangement of the parts as shown, the stepped stop 133, arranged at the right of the series of column stops 51, is effective for selecting different denominational positions of arrest in the last column for monetary work, for example. Thus it will be understood that after the column stops 51 have passed the stop 82 in the movement of the carriage from right to left, a movement of the selecting key 86 to any one of the sixteen positions to which it may be adjusted, is effective to bring the selecting stop 82 into register with any one of the sixteen stepped faces 137 on the stepped stop. A subsequent complete depression of the key 115 is effective to release the carriage and bring about an arrest thereof at the selected denominational position in the last column. It will be seen, therefore, that the selecting key 86 at one time operates as a column selecting key and at another time as a denominational selecting key, depending on the position of the carriage in its line of travel. The particular arrangement of the stepped stops shown in the present instance affords the selection of sixteen different denominational positions. For British monetary work, for example, this would afford a selection up to and including the tens of thousands positions for pounds, with the provision of a comma between the hundreds and thousands positions. It would also provide for three spaces between pounds and shillings; two positions for shillings; three spaces between shillings and pence, and two positions for pence, thus oc-

cupying the sixteen denominational positions of arrest that may be selected under the example shown. The index plate 126 may be provided with a series of indices in the spaces 131 at the left-hand portions thereof to designate the pounds, shillings and pence arrangement referred to above, or any suitable inscriptions may be made on the index plate to correspond to the sixteen different denominational positions of arrest afforded by the coöperation of the selecting stop 82 with the stepped stop 133.

From the foregoing description it will be understood that I have provided simple and efficient means by which a large number of columns may be selected during a single travel of the carriage; that the stop 82 is movable transversely of the paths of movement of the contact portions 53 to set the stop 82 into register with the contact portion of one or another stop 51; that the key 115 is operative to move the stop 82 into and out of coöperative relation with the registering contact 53; that the construction is such that the tabulating mechanism is automatically rendered operative at one time as a column selector and at another time as a denominational selector, as determined by the position of the carriage in its line of travel; that the relative adjustment of the stops 51 and 133 determines at what point in the travel of the carriage the tabulating mechanism shall be operative or effective for one character of selection and not for the other, and also determines whether the tabulating mechanism shall be operative first as a column selector and then as a denominational selector or vice versa; that the employment of one character of stops 51 or 133 to the exclusion of the other determines whether the tabulating mechanism shall be operative exclusively and indefinitely as a column selector or as a denominational selector and that the same keys 86 and 115 and the same stop 82 are operative at one time for column selection and at another time for denominational selection.

I am aware that various changes in the construction may be made without departing from the spirit and scope of my invention and it should be understood, therefore, the accompanying drawings illustrate but one form of construction embodying and illustrating my invention. Moreover, it should be understood that various features of the construction may be employed without others.

What I claim as new and desire to secure by Letters Patent, is:—

1. In a typewriting machine, the combination of a carriage, a series of column stops carried thereby and the contact portion on each of which has a separate and distinct path of movement, a single coöperative se-

lecting stop which is settable transversely of the paths of the movement of said contact portions to merely set the coöperative stop into register with the contact portion of one or another of said column stops, a single selecting key for so setting said coöperative stop into register with the contact portions on different column stops, and key controlled means for moving the set coöperative stop into and out of coöperative relation with the registering column stop.

2. In a typewriting machine, the combination of a carriage, a series of column stops carried by the carriage and the contact portion on each of which stops extends rearwardly therefrom and has a separate and distinct path of movement, a single coöperative column selecting stop that is movable vertically to set it in register with the contact on one or another of the different column stops, a single selecting key for controlling the vertical movement of the column selecting stop and for merely setting it in register with the contacts on different column stops, and key controlled means for moving said column selecting stop fore and aft of the machine and into and out of coöperative relation with the contact with which it has been set in register and for releasing the carriage.

3. In a typewriting machine, the combination of a carriage, a series of column stops carried thereby and each of said stops having a contact portion that has a separate and distinct path of movement, a column selecting stop that is movable in one direction and may be set by such movement into register with any of said contacts, a single variably movable key which controls the setting of said column selecting stop, means for maintaining indefinitely in any of the variable positions to which they may be moved said key and column selecting stop, and a separate independently operable key for moving said column selecting stop at substantially right angles to its setting movement in order to move the column selecting stop into and out of the path of the registering contact and for simultaneously releasing the carriage.

4. In a typewriting machine, the combination of a carriage, a series of column stops carried by and adjustable on said carriage and the contact on each of which stops has a separate and distinct path of movement, a single coöperative selecting stop that has a variable rectilinear movement to set it into register with the contacts on the different column stops without bringing it into the paths thereof, a single variably movable key which controls the rectilinear setting movement of said column selecting stop, and separate independently operable means for controlling the movement of said selecting stop into and out of the path of the contact

of the adjustable stop with which the selecting stop is in register.

5. In a typewriting machine, the combination of a carriage; and tabulating mechanism comprising a single stop which may be set to any one of a plurality of positions to select the position of arrest of the carriage, a variably movable key which controls the setting of said stop and which key remains indefinitely in any of the variable positions to which it may be set, and separate independently operable means for moving said stop into operative position.

6. In a typewriting machine, the combination of a carriage; and tabulating mechanism comprising a single stop which may be set to any one of a plurality of positions to select the position of arrest of the carriage, a variably movable key which controls the setting of said stop and which key remains indefinitely in any of the variable positions to which it may be set, an index with which said key coöperates, and separate independently operable means for moving said stop into operative position and for simultaneously releasing the carriage.

7. In a typewriting machine, the combination of a carriage; and tabulating mechanism comprising a series of adjustable stops carried by the carriage, a single coöperative stop which may be set to any one of a plurality of positions to co-act with any of said adjustable stops and thus select the position of arrest of the carriage, a variably movable key which controls the setting of said coöperative stop and which key remains indefinitely in any of the variable positions to which it may be set, and an index with which said key coöperates.

40 8. In a typewriting machine, the combination of a carriage; and tabulating mechanism comprising a series of adjustable stops, a single coöperative stop which may be set to any one of a plurality of positions to select the position of arrest of the carriage, a variably movable key which controls the setting of said coöperative stop and which stop remains indefinitely in any of the variable positions to which it may be set, an index with which said key coöperates, a separate key, and means controlled thereby for moving the coöperative stop into coöperative relation with the adjustable stop with which it has been set to register and for simultaneously releasing the carriage.

9. In a typewriting machine, the combination of a carriage; and tabulating mechanism comprising a series of adjustable stops carried by the carriage, each of said stops having a contact portion that has a separate and distinct path of movement, a single coöperative stop carried by the frame of the machine and which may be set to any one of a plurality of positions in register with a contact on one of the adjustable stops in

order to select the position of arrest of the carriage, a variably movable key which controls the setting of said coöperative stop and which key remains indefinitely in any of the variable positions to which it may be set, 75 an index with which said key coöperates, a separate key, and means controlled thereby for moving the coöperative stop into coöperative relation with the contact on the adjustable stop with which it has been set to 75 register.

10. In a typewriting machine, the combination of a carriage; and tabulating mechanism comprising coöperative stops, key controlled means for moving one of said stops 80 into the path of the other, and means for at will either releasing the carriage during the interposing of one stop in the path of another or for merely interposing such stop without releasing the carriage.

85 11. In a typewriting machine, the combination of a carriage, tabulating mechanism comprising coöperative stops, key controlled means for moving one of said stops into the path of the other, means for releasing the carriage during the interposing of one stop in the path of another, and means for preventing release of the carriage without interfering with such positioning of said stop.

90 12. In a typewriting machine, the combination of a carriage, tabulating mechanism comprising stops coöperative to arrest the carriage during both a backward and a forward movement thereof, key controlled means for moving one of said stops into the 100 path of the other, means for releasing the carriage during the interposing of one stop in the path of another, and means permitting such interposing of stops but preventing the release of the carriage.

125 13. In a typewriting machine, the combination of a carriage; and tabulating mechanism comprising coöperative tabulator stops, means by which said stops are effective to arrest the carriage at the same letter-space 110 position during a backward tabulation that they are to arrest the carriage during a forward tabulation, key controlled means for moving one of said stops into the path of the other, and means by which a release of the 115 carriage may be effected as one stop is interposed in the path of the other and means by which such interpositioning may be effected without releasing the carriage as may be desired, whereby the carriage may be released for forward tabulation when one stop is interposed in the path of the other and such interpositioning of the stop may be effected during backward tabulation without releasing the carriage.

14. In a typewriting machine, the combination of a carriage, tabulating mechanism comprising two stops, a key for moving one of said stops into coöperative relation with the other, means by which said key is op- 130

erative to release the carriage when the stops are being brought into coöperative relation, and means for at will preventing the release of the carriage when said stops are brought into coöperative relation.

15. In a typewriting machine, the combination of a carriage; and tabulating mechanism comprising two stops, a key for moving one of said stops into coöperative relation with the other, and means by which said key is operative to release the carriage when the stops are being brought into coöperative relation or to enable the stops to be brought into coöperative relation without effecting a release of the carriage, as may be desired, said key having two paths of movement which determine whether or not the carriage shall be released when the stops are being brought into coöperative relation.

20. In a typewriting machine, the combination of a carriage; and tabulating mechanism comprising two stops, a key for moving one of said stops into coöperative relation with the other, means by which said key is operative to release the carriage when the stops are being brought into coöperative relation or to enable the stops to be brought into coöperative relation without effecting a release of the carriage as may be desired, the extent of dip of said key determining whether or not the carriage shall be released when the stops are being brought into coöperative relation, and two stops either of which may be rendered effective to control the extent of dip of the key.

25. In a typewriting machine, the combination of a carriage, tabulating mechanism comprising a series of stops, a coöperative stop, a key, means controlled by said key for merely setting said coöperative stop in register with any one of the series of stops, a second key for moving the coöperative stop into the path of movement of the stop 45 with which it has been registered, means connected to said second key for releasing said carriage when said second key is actuated, and means whereby said second key may be actuated to interpose said coöperative stop without releasing the carriage.

30. In a typewriting machine, the combination of a carriage; and tabulating mechanism comprising a series of tabulator stops, a coöperative stop each side of which co-55 acts with the series of stops to arrest the carriage, for forward and backward tabulation, and means for affording a relative movement between the series of stops and the part of the machine by which they are carried when the coöperative stop engages one of the series of stops, such relative movement corresponding substantially to the thickness of the engaged stops.

35. In a typewriting machine, the combination of a carriage; and tabulating mecha-

nism comprising a series of tabulator stops, a coöperative stop each side of which co-acts with the series of stops to arrest the carriage, for forward and backward tabulation, means for affording a relative movement between the series of stops and the part of the machine by which they are carried when the coöperative stop engages one of the series of stops, such relative movement corresponding substantially to the thickness of the engaged stops, and a spring for effecting a relative return movement between the series of stops and the part of the machine which carries it after a disengagement is effected between the stops.

40. In a typewriting machine, the combination of a carriage; and tabulating mechanism comprising a series of tabulator stops carried by the carriage, a key controlled coöperative tabulator stop carried by the frame of the machine, and means for affording a movement of the carriage independently of said series of stops after one of the series of stops is engaged by said key-controlled stop, the independent movement 90 between the carriage and said series of stops corresponding substantially to the thickness of the engaged stops.

45. In a typewriting machine, the combination of a carriage; and tabulating mechanism comprising a series of tabulator stops carried by the carriage, a key controlled coöperative tabulator stop carried by the frame of the machine, means for affording a movement of the carriage independently 100 of said series of stops after one of the series of stops is engaged by said key-controlled stop, the independent movement between the carriage and said series of stops corresponding substantially to the thickness 105 of the engaged stops; and a spring for returning the series of stops to normal position on the carriage after the disengagement between the stops.

50. In a typewriting machine, the combination of a carriage; and tabulator mechanism comprising a stop bar, a series of stops carried thereby, a coöperative stop each side of which is operative to co-act therewith, for backward and forward tabulation, and means for affording a relative movement between said stop bar and the part of the machine which carries it for a distance corresponding substantially to the thickness of two of said stops.

55. In a typewriting machine, the combination of a carriage; and tabulating mechanism comprising a series of stops, a coöperative stop, and means for arresting the carriage at the same letter space position 125 by the coöperation of said coöperative stop with one of the series of stops during both a backward and a forward tabulation, said means including means for affording a limited relative movement in one direction be- 130

tween the series of stops and the support therefor after the coöperative stop and one of the series of stops engage each other and while said engaged stops remain stationary.

5 24. In a typewriting machine, the combination of a carriage; and tabulating mechanism comprising a series of stops carried by the carriage; a coöperative stop, and means for arresting the carriage at the same letter space position by the coöperation of said coöperative stop with one of the series of stops during both a backward and a forward tabulation, said means including means for affording a limited movement of the carriage 10 in one direction independently of the said series of stops after an engagement between the coöperative stop and one of the series of stops has been effected.

20 25. In a typewriting machine, the combination of a carriage; and tabulating mechanism comprising a series of stops carried by the carriage, a coöperative stop, and means for arresting the carriage at the same letter space position by the coöperation of 25 said coöperative stop with one of the series of stops during both a backward and a forward tabulation, said means including a stop bar on which said series of stops are mounted, and means for affording a relative 30 movement between said stop bar and the part of the machine which carries it for a distance corresponding substantially to the thickness of two of said stops.

35 26. In a typewriting machine, the combination of a carriage; and tabulating mechanism comprising a series of stops carried by the carriage, a coöperative stop, and means for arresting the carriage at the same letter space position by the coöperation 40 of said coöperative stop with one of the series of stops during both a backward and a forward tabulation, said means including a stop bar carried by the carriage and on which said series of stops are mounted, and means for affording a relative 45 movement between the carriage and said stop bar for a distance corresponding substantially to the thickness of two of said stops, and a spring which returns the stop bar to 50 a normal position on the carriage after the engaged stops have been disengaged.

55 27. In a typewriting machine, the combination of a carriage, a series of column stops each having a contact portion that has a separate and distinct path of movement parallel with the carriage movement, a stepped stop, a coöperative stop, and key controlled means for bringing said coöperative stop into coöperative relation with a 60 contact portion on any of said column stops and with any stepped contact face on the stepped stop.

65 28. In a typewriting machine, the combination of a carriage, a series of column stops each having a contact portion that has

a separate and distinct path of movement, a stepped stop, each stepped contact face of which has a path of movement which corresponds to a path of movement of a contact portion on one of the column stops, a coöperative stop, and key controlled means for bringing said coöperative stop into coöperative relation with a contact portion on any of said column stops and with any stepped contact face on the stepped stop. 70

75 29. In a typewriting machine, the combination of a carriage, a series of column stops each having a contact portion that has a separate and distinct path of movement, a single stepped stop at one end of the series of column stops, a coöperative stop, and key controlled means for bringing said coöperative stop into coöperative relation with a contact portion on any of said column stops and with any stepped contact face on the stepped stop. 80

85 30. In a typewriting machine, the combination of a carriage; and tabulating mechanism comprising a double rack, a series of stops received between the opposite engaging faces of said double rack, and a double locking bar coöperative with the stops to prevent them from being disengaged from said double rack. 90

95 31. In a typewriting machine, the combination of a carriage; and tabulating mechanism comprising a double rack, a series of stops received between the opposite engaging faces of said double rack, two locking bars coöperative with the stops at 100 opposite ends thereof to prevent them from being disengaged from said double rack, and a single finger piece for controlling the movement of said locking bars into and out of locking position. 105

110 32. In a typewriting machine, the combination of a carriage; and tabulating mechanism comprising a double rack, a series of stops received between the opposite engaging faces of said double rack, two locking bars coöperative with the stops to prevent them from being disengaged from said double rack, a spring which tends to move said locking bars to the locking position, and hand actuated means for moving said locking bars against the power of said spring and away from the locking positions. 115

120 33. In a typewriting machine, the combination of a carriage; and tabulating mechanism including a rack, a series of stops which engage said rack, two locking bars which co-act with said stops and hold them from withdrawal from the rack, and hand actuated means for simultaneously moving both locking bars to the releasing position. 125

130 34. In a typewriting machine, the combination of a carriage; and tabulating mechanism including two rack bars which are

- spaced apart and have their teeth extending toward each other, stops which are received between said rack bars in the spaces between the teeth thereof, two locking bars for locking the stops against withdrawal from between said rack bars, and means for effecting a simultaneous movement of both of said locking bars into and out of locking position. 70
35. In a typewriting machine, the combination of a carriage; and tabulating mechanism including two rack bars which are spaced apart and have their teeth extending toward each other, stops which are received between said rack bars in the spaces between the teeth thereof, two locking bars for locking the stops against withdrawal from between said rack bars, toggle links between said locking bars, a finger piece which controls said toggle links, and a spring which tends to move said locking bars to locking position. 75
36. In a typewriting machine, the combination of a carriage; and tabulating mechanism including two rack bars which are spaced apart and have their teeth extending toward each other, stops which are received between said rack bars in the spaces between the teeth thereof, two locking bars for locking the stops against withdrawal from between said rack bars, toggle links between said locking bars, a finger piece which controls said toggle links, and a spring which tends to move said locking bars to locking position, a straightening of the toggle links dead centering them and holding the locking bars in the released position against the power of said spring. 80
37. In a typewriting machine, the combination with a series of detachable tabulator stops, of means for locking the stops against detachment, said means comprising a pair of locking bars movable into and out of locking position, and means for simultaneously moving both of said locking bars. 85
38. In a typewriting machine, the combination with a series of detachable tabulator stops, of means for locking the stops against detachment, said means comprising a pair of locking bars movable toward and away from each other into and out of locking position, toggle links between said locking bars for causing them to move simultaneously into and out of operative position, and a finger piece connected with said links. 90
39. In a typewriting machine, the combination with a series of detachable tabulator stops, of means for locking the stops against detachment, said means comprising a pair of locking bars movable toward and away from each other into and out of locking position, toggle links between said locking bars for causing them to move simultaneously into and out of operative position, a finger piece connected with said links, and a spring connecting said locking bars and tending to draw them together, a straightening of the toggle links dead centering the links and holding the locking bars in the released position against the power of said spring. 95
40. In a typewriting machine and in tabulating mechanism, the combination of tabulator stops coöperative to arrest the carriage at a predetermined point, means including a key for effecting such coöperation, carriage releasing devices controlled by said key, and means for rendering said key ineffective on said carriage releasing devices. 100
41. The combination of a carriage, a series of column stops, a series of denominational stops, a single stop adapted to co-act at different times with both the series of column stops and the series of denominational stops, and key actuated means for projecting said co-acting stop into coöperative relation with said column stops and said denominational stops. 105
42. The combination of a carriage, a series of adjustable column stops, a series of denominational stops, and a co-acting stop adapted at different times to engage both said series of column stops and said series of denominational stops. 110
43. In a typewriting machine, the combination of a carriage; and tabulating mechanism comprising a key and means by which the position of the carriage in its line of travel determines whether said key shall be operative to select different columnar fields or different denominational positions. 115
44. In a typewriting machine, the combination of a carriage; and tabulating mechanism comprising traveling stops of two different characters, and a single key controlled stop coöperative with traveling stops of one character for column selection and coöperative with traveling stops of another character for denominational selection. 120
45. In a typewriting machine, the combination of a carriage; and tabulating mechanism comprising a stop and actuating keys, said keys and said stop being operative at one time for column selection and at another time for denominational selection, the change of conditions taking place automatically. 125
46. In a typewriting machine, the combination of a carriage, a set of column stops arranged thereon, a coöperating stop, a single key for moving said coöperative stop in the direction of the series of column stops, so as to align with any selected one of said column stops, and separate means for moving said coöperative stop into the path of travel of the selected column stop. 130
47. In a typewriting machine, the combination of a carriage, a set of column stops arranged thereon, a coöperating stop, a single key for moving said coöperative stop in the direction of the series of column stops, so as to align with any selected one of said

column stops, separate means for moving said coöperative stop into the path of travel of the selected column stop, and means for releasing the carriage also actuated by the 5 means that interposes the coöperative stop in the path of the selected column stop.

48. The combination of a carriage, a series of stops thereon, each stop arranged to travel in a different horizontal path, a key- 10 actuated coöperative stop moved by a single key into alinement with any selected one of

said stops, and separate means for subsequently moving said coöperative stop into the path of travel of the selected stop.

In testimony whereof I have signed my 15 name to this specification in the presence of two subscribing witnesses.

SAMUEL WILLIAM TURNER.
